COMBINED REFLECTOR AND LENS

Sidney A. Heenan, Park Ridge, and Eugene A. Peterson,
Northbrook, Ill., assignors to Amerace Esna Corporation,
Union, N.J., a corporation of Delaware

Filed June 30, 1969, Ser. No. 17,978

Term of patent 14 years

Int. Cl. D12—99; D26—06; D29—99

U.S. Cl. D48—32

FIG. 1**FIG. 2****FIG. 3****FIG. 4**FIG. 5 ←-6

FIG. 6

←-8 FIG. 7

FIG. 8

FIG. 1 is a front elevational view of a combined reflector and lens incorporating our new design;

FIG. 2 is a fragmentary rear elevational view on a greatly enlarged scale;

FIG. 3 is a sectional view on an enlarged scale, taken along the line 3-3 of FIG. 1;

FIG. 4 is a sectional view taken along the line 4-4 of FIG. 2;

FIG. 5 is a front elevational view of a combined reflector and lens incorporating another embodiment of our new design;

FIG. 6 is a sectional view taken along the line 6-6 of FIG. 5;

FIG. 7 is a fragmentary rear elevational view on an enlarged scale; and

FIG. 8 is a sectional view taken along the line 8-8 of FIG. 7.

We claim:

The ornamental design for a combined reflector and lens, substantially as shown and described.
